Mr. Nicholas Müller's Design for

Clock Case.

Patented Aug 7, 1865.

At the Office of the

Patent Office, Washington, D. C.

Des. 2377

Nicholas Miller, New York, N. Y.

Letters Patent No. 2377. Dated Aug. 7, 1866.

Design for Clock Case

The Schedule referred to in these Letters Patent and making part of the same.

To all whom it may concern: -

Be it known that, & Nicholas Miller, of the City, County, and State of New York have invented a new and improved Design for clock base; and & do hereby declare that the following is a full, clear, and exact description thereof, which will enable others skilled in the art to make and use the same, reference being had to the accompanying drawings forming part of this specification, in which:

Figure 1, represents a front elevation of this invention.

Figure 2, is a side elevation of the same.

Figure 3, is a transverse section of the same, the line a, b, indicating the plane of section.

Similar letters of reference indicate like parts.

The distinguishing features of this present Design are, a wreath A, of flowers which is situated on the top of the clock case and which is composed principally of roses and violets intermixed.

On one side of the clock base is applied a round book B, partly covered by a wreath C, of vine leaves, grapes and laurel and on the opposite side of the case is a gavel D, filled with arrows, and a canteen E,

The bottom part of the case is ornamented by a circular wreath F, from which emanates two laurel branches G, the whole being combined to produce a new and ornamental Design.

That I claim as new and desire to secure by Letters Patent is, A Design for a clock base as shown and described.

The above specification of my invention signed by me this 30th day of June 1866.
